 Helen Cramer Hoffman, Paterson, N. J.

Application October 18, 1934, Serial No. 748,830

9 Claims. (Cl. 215—32)

This invention relates to a bottle and particularly to an arrangement for sealing the bottle with a simple and effective seal which cannot be replaced once it has been removed.

5 An object of the invention is to provide a sealing means which is formed in the neck of the bottle and permanently secured therein, either before or after filling the bottle.

Another object is to provide a sealing means 10 which can be seen readily in the neck of the bottle, so that any change in its condition can be noted.

Another object is to provide a glass sealing means in a glass bottle such that the contents of the bottle may come in contact only with glass.

15 A still further object is to provide certain improvements in the form, construction, arrangement, and material whereby the above named and other objects may effectively be attained.

A practical embodiment of the invention is represented in the accompanying drawing, in which

Fig. 1 represents, in vertical section, the neck of a bottle with a sealing bulb and tube ready to be blown into sealing position;

Fig. 2 represents, in vertical section, the neck of a bottle with the bulb blown into position against the side of the neck;

Fig. 3 represents, in vertical section, the neck of a bottle in its filled, sealed and capped condition;

Fig. 4 represents, in vertical section, the neck 30 of a bottle with the cap removed and the seal broken, i. e., in normal condition for use;

Fig. 5 represents, in vertical section, a modified arrangement for securing the sealing bulb into the neck of a bottle;

35 Fig. 6 represents, in vertical section, a modified arrangement permitting the use of a cork as an outer closure instead of the cap shown in Fig. 3;

Fig. 7 represents, in vertical section, a detail of a modified arrangement for securing a sealing 40 means in the neck of a bottle; and

Fig. 8 represents, in vertical section, a detail of another modified arrangement for securing a sealing means in the neck of a bottle.

Referring to the drawing, the bottle and its 45 seal may conveniently be described by setting forth the steps of one method which may be advantageously used in its manufacture. A bottle having a neck 2 is molded so as to form an inwardly projecting shoulder 3 at or near the base of the neck. The inner surface of the neck immediately above the shoulder 3 will normally assume a somewhat concave shape, as shown at 4, and this concavity may be increased or controlled as desired in a manner well known to those skilled 50 in the bottle making art.

While the bottle is still hot and slightly plastic, a glass tube 5 having its lower end partially blown in the form of a bulb 6 is introduced into the neck 2 of the bottle, to approximately the distance shown in Fig. 1; the blowing of the bulb 6 is then continued until it reaches the position shown in Fig. 2, wherein the bulb is intimately engaged with the neck of the bottle along the concave portion 4 thereof. This engagement should be effected at a sufficiently high temperature so that the bulb 6 will actually fuse to the neck of the bottle.

Preferably before the bulb 6 has entirely lost its plastic condition a piercing tool of any suitable character is introduced through the tube 5 in 15 order to puncture the bottom of the bulb 6, forming an opening 7, as shown in Fig. 3. The bottle may then be finished in any usual manner, as by cooling, annealing, etc., up to the point where it is ready to be filled. It will be understood that 20 the tube 5 is open at its top, as shown in Figs. 1 and 2, and the bulb 6 has the opening 7 in its bottom, hence the contents of the bottle may readily be introduced therein through the tube and bulb.

When the bottle has been filled as just described, fusing heat is applied to the tube 5 at a point slightly above the top of the bottle neck and the tube is thus sealed closed, as shown at 8, in Fig. 3. Either before or after filling and sealing 30 the bottle, a diamond tool or the like is introduced into the neck of the bottle and a groove 9 is cut completely around the outer surface of the tube 5 at or near its lower end. A protective metal cap or reclosure 10, arranged to project beyond 35 the sealed end 8 of the tube, is provided, and the bottle is then complete and ready for shipment and sale.

When it is desired to remove the contents of the bottle, the cap 10 is taken off, a slight lateral 40 pressure is applied to the projecting end of the tube 5, and the tube breaks off cleanly at the line of the groove 9, thus permitting the contents of the bottle to be poured through the openings 7 and 11 at the bottom and top of the bulb 45 6, as shown in Fig. 4.

After use, the bottle may be reclosed by means of the cap 10, but it will be impossible to replace the tube securely on the bulb by any means which would not be readily apparent to a subsequent 50 user. The composition of the glass forming the tube 5 should be such that there can be no possibility of any splinters occurring when the tube is broken, but the line of break will always have certain characteristic irregularities which will 55

prevent any tube but the original one from fitting exactly. A new tube could not be fused on to the bulb because the heat either would cause the tube end to close or would crack the bulb; 5 and a new tube and bulb could not be inserted (assuming that the original bulb could be more or less completely removed) because, again, the heat would crack the neck of the bottle. In case the bottle is composed of clear or light colored 10 glass it may be desirable to make the tube and bulb of some darker color, in order to facilitate inspection of the seal and detection of any tampering therewith.

The bottle construction shown in Figs. 1 to 4 inclusive provides for engagement of the bulb with a concave surface on the inside of the bottle neck, as already explained, and it will be apparent that in this case it would be impossible to replace the original seal with a new fully 20 formed bulb in any way which would permit close engagement with the concave portion 4 of the bottle neck, even if the inner surface of the neck should be cylindrical or flaring outwardly above the concave portion. In the modification 25 shown in Fig. 5, the bottle neck 12 has no internal concavity and the bulb 13 engages the neck, preferably by fusion therewith, along a straight frusto-conical or cylindrical surface. Insertion of a new fully formed bulb and tube may then be prevented by making the internal diameter of the 30 bottle neck smaller at a point above the bulb than at the point where the bulb is located. This may conveniently be accomplished by tapering the neck of the bottle toward its top, as shown 35 in Fig. 5, or by providing an internal ridge or lip between the bulb and the top of the neck, as will readily be understood.

The modification shown in Fig. 6 is designed to permit the use of a cork 14, preferably having 40 a projecting top handle portion 15, in place of the cap 10, shown in Figs. 3 and 5. In this case the tube 16 may be heated to the fusing point by suitable means (as an electric coil or the like) at a point below the top of the bottle neck, thus 45 forming a sealed closure 17 below the bottom of the cork. A groove 18 may be formed as before, and the contents of the bottle may be made available for use by breaking off and removing the tube 16. The tube 16 is shown attached to a bulb similar to that shown in Figs. 1 to 4, but it 50 will be understood that this arrangement could be adapted equally well to the form of bulb shown in Figs. 5, 7 or 8.

A modified arrangement for securing the bulb 55 in the bottle is shown in Fig. 7, where the base of the bottle neck is brought inward to form a shoulder 19, narrower than any part of the neck above said shoulder. A bulb 20, suitably shaped to engage the shoulder 19 is inserted fully formed 60 to the position shown, and is sealed in place by a filling of cement or other solidifiable sealing material 21. This bulb bears a tube 22, which may be either of the type shown in Fig. 3 or of the type shown in Fig. 6, and a groove 23 is provided as before. Fraudulent replacement of the 65 tube and bulb portion in this arrangement may be prevented by the use of a cement or the like which cannot be dissolved or removed without leaving some mark on the neck of the bottle. It 70 will be noted that in this form also the contents of the bottle is in contact only with glass surfaces.

In cases where a close fit between the neck and the bulb cannot be assured, it may be desirable to provide an arrangement such as that 75 shown in Fig. 8 wherein a lower projecting part

24 of the sealing means bears a washer or stopper 25 which projects laterally a suitable distance to engage securely the lower part of the bottle neck, whether provided with a shoulder or not. This form of construction may conveniently be used when the bottle is to be filled before inserting the sealing means, since the sealing material 26 is kept out of contact with the contents of the bottle by the close fitting washer or stopper 25.

While the invention herein has been described particularly in connection with bottles it is apparent that in some cases it might be adapted to use in jugs or other containers, composed of glass or earthenware or other materials to which a glass bulb can satisfactorily be fused or cemented. 15 It will be understood that various changes may be resorted to in the construction, form, arrangement and materials of the several parts without departing from the spirit and scope of the invention, and hence I do not intend to be limited 20 to the details herein shown and described except as they may be included in the claims.

What I claim is:

1. A bottle having a sealing means secured in the neck thereof, said means comprising, a bulb 25 portion intimately engaged with the neck of the bottle and an upwardly projecting tube portion sealed at its upper end and connecting with the bulb portion at its lower end.

2. A bottle having a sealing means secured in 30 the neck thereof, said means comprising, a glass bulb portion intimately engaged with the neck of the bottle, an upwardly projecting glass tube portion sealed at its upper end, connecting with the bulb portion at its lower end and separable therefrom by breaking, and means for determining the 35 position of the break.

3. A bottle having a sealing means secured in the neck thereof, said neck having a concave portion, said sealing means comprising a glass 40 bulb portion intimately engaged with said concave portion of the neck, and an upwardly projecting glass tube portion sealed at its upper end, integral with the bulb portion at its lower end and separable therefrom by breaking. 45

4. A bottle having a sealing means secured in the neck thereof, said means comprising, an extended portion adapted to engage the neck of the bottle and a tube portion sealed at its upper end, secured to the extended portion at its lower 50 end and terminating a sufficient distance below the top of the bottle neck to permit the introduction of a cork stopper therein.

5. A bottle having a sealing means secured in the neck thereof, said means comprising an ex- 55 tended portion adapted to engage the neck of the bottle, and a portion of the neck between the top thereof and the point of engagement of said extended portion being less in internal diameter than the diameter of the extended portion. 60

6. A bottle having a sealing means secured in the neck thereof, said sealing means comprising a tube portion, means extending between the tube portion and the bottle neck and spaced from the top of the neck, and means for securing said 65 tube portion permanently in position within the bottle neck.

7. A bottle having a sealing means secured in the neck thereof, said neck having an inwardly projecting shoulder spaced from the top of the 70 neck, said sealing means comprising an extended portion adapted to engage with said shoulder, and means for securing said extended portion permanently in engagement with the shoulder.

8. A bottle having a sealing means secured in 75

the neck thereof, said sealing means comprising a tube portion, means extending between the tube portion and the bottle neck, and a filling of cement for securing said tube portion permanently in position within the bottle neck.

5 9. A bottle having a sealing means secured in the neck thereof, said sealing means comprising a

tube portion, means including a washer extending between the tube portion and the bottle neck, and a filling of cement for securing said tube portion permanently in position within the bottle neck.

5 ALFRED HOFFMAN.
